H. G. WARR

RAIL ANCHOR

Filed June 25, 1923

UNITED STATES PATENT OFFICE.

HAROLD G. WARR, OF PARK RIDGE, ILLINOIS, ASSIGNOR TO THE P. & M. COMPANY,
OF CHICAGO, ILLINOIS, A CORPORATION OF ILLINOIS.

RAIL ANCHOR.

Application filed June 25, 1923. Serial No. 647,645.

To all whom it may concern:

Be it known that I, HAROLD G. WARR, a citizen of the United States, residing at Park Ridge, in the county of Cook and State 5 of Illinois, have invented certain new and useful Improvements in Rail Anchors, of which the following is a specification.

My invention relates to rail anchors, and has for its primary object the provision of 10 an improved rail anchor which will maintain a firm grip on a rail, which may be conveniently applied to or removed from a rail when desired, and which will fit rails having base flanges of different sizes.

15 A further and more specific object of the invention is the provision of an improved two-piece anchor device consisting of a jaw member and a key or wedge member which together grip one or both edges of a rail 20 base, which are so constructed that either or both members may be conveniently formed from sheet metal, and which when applied to a rail will provide a resilient interlocking engagement of the members, 25 one within the other, so as to maintain the key or wedge member in its applied wedging position.

The invention further consists of the new and improved constructions and arrangement of parts, hereinafter described and claimed, for carrying out the above stated objects, and such other objects as will appear from the following description of the embodiments of the invention illustrated in 35 the accompanying drawing.

In the drawing:

Fig. 1 is a face view, partly in elevation and partly in section, of a rail anchor device constructed in accordance with my invention, showing the same applied to the base flange of a rail.

Fig. 2 is a plan view in elevation of the rail anchor shown in Fig. 1, the outline of the rail base for the purpose of clearness being illustrated in dot-and-dash lines in this figure.

Fig. 3 is a cross-section taken on line 3—3 of Fig. 1.

Fig. 4 is a view similar to Fig. 1, illustrating a modified embodiment of the invention; and

Fig. 5 is a sectional plan view, taken on line 5—5 of Fig. 4.

Like characters of reference designate like parts in the several figures of the drawing.

Referring to Figs. 1 to 3 inclusive, wherein I have shown one embodiment of my invention as consisting of a jaw member 10 and a key or wedge member 11, either or both of which may be made of spring steel, and which together grip the upper and lower surfaces of the rail base 12. The jaw member is preferably, although not necessarily, made of sheet metal and is in the form of a yoke having a channel-shaped body portion 13 which extends across the rail base. When the yoke is made of sheet metal, it is preferably provided at each end with a pair of spaced jaws 14, 14 and 15, 15, 60 adapted to project over and bear against the inclined upper surface of the rail base 12 at opposite sides of the rail. The jaws at one end of the yoke, for example, jaws 15, 15, are somewhat longer than the jaws 70 at the other end of the yoke, so as to provide sufficient clearance to permit the pairs of jaws 14, 14 and 15, 15 to be hooked over the opposite edges of the rail base. The lower edges of the jaws 15, 15 are provided 75 with shoulders 16 adapted to abut against the adjacent vertical edge of the rail base, so as to prevent any substantial accidental displacement of the yoke transversely of the rail. The length of the jaws 15, 15, will, 80 ordinarily, depend upon the height and length of the jaws at the other end of the yoke, and also the amount of clearance between the bottom surface of the rail base 85 and the upper edge of the yoke body. The 90 body portion of the yoke is preferably substantially U-shaped in cross-section, and is tapered longitudinally in depth and width, so that it is narrower and deeper at one end than at the other.

95 The key is preferably made of spring metal, and is substantially U-shaped in cross-section. It is also tapered so that it increases in width and decreases in depth toward one end, thereby providing the wedge surface 17 (see Fig. 1), which cooperates with the corresponding tapered surface 18 of the yoke to effect a wedging engagement of the key between the rail base and the yoke when the key is forced toward the shallow 105 end 19 of the yoke. The sides 20, 20 of the

yoke being tapered so that the channel portion decreases in width toward the end 21 of the yoke at which the key enters, and the bottom being tapered in the opposite direction, 5 there is formed in effect a pocket in which the key is held by the resilient gripping action of the member. The resiliency of either or both members 10 and 11, as the case may be, permits the wide portion of the key 11 10 to be driven through the narrow opening 21 of the yoke. As the key moves inwardly toward the wider and shallower end 19 of the yoke, the key expands so as to conform to the tapered sides of the channel.

15 With this construction the expansion of the key and also the contraction of the walls 20, 20 of the yoke exert spring pressure against both members so as to effect a resili- 20 ent interlocking engagement.

20 In order to facilitate the entrance of the wide end of the key into the narrow end 21 of the channel of the yoke, the end of the yoke is preferably flared outwardly, as in- 25 dicated by the reference numeral 22. The entrance end of the key may be, and pref- 30 erably is, turned slightly inward, as indi- cated by the numeral 23, so that the key can be easily started through the narrow end 21 of the channel 13.

30 In applying the anchor to a rail, the pair of jaws 15, 15 are first hooked over one edge of the rail base. The recesses defining the lower edges of these jaws are of sufficient depth to permit the yoke to be moved 35 to the right in Fig. 1, a distance sufficient to permit the jaws 14, 14 to be hooked over the other edge of the rail base. The yoke may then be moved to its normal position as shown in Fig. 1. In this position the 40 channel shaped body of the yoke is ar- ranged against the vertical face of an adja- cent cross-tie 24 and the key 11 is forced to its wedging position, as above described. The channel-shaped construction rigidifies 45 the yoke longitudinally, but permits slight distortion or flexing of the sides of the yoke laterally. The key shown in Figs. 1 to 3 inclusive is preferably relatively short and assumes its wedging position substantially 50 at the center of the rail base. When a key of this construction is used, it may be driven to its wedging position with the end of a crowbar (not shown), or other suitable im- 55 plement that may be conveniently used as a ram. The wedging pressure against the upper edges of the key has a tendency to force it to conform to the contour of the channel. With this construction it will be seen that the key cannot move in the direc- 60 tion from which it was driven without itself contracting or effecting an expansion of the constricted opening 21 of the channel portion of the yoke.

65 In Figs. 4 and 5 I have illustrated an- other embodiment of my invention in which

the key designated 11^a in these figures is of substantially the same length as the yoke member, thereby making it possible to apply the key to its wedging position without the use of a ram. The yoke and key mem- 70 bers of this embodiment are the same as those shown in Figs. 1 to 3 inclusive, with the exception that the key 11^a is somewhat longer than the key shown in the previous figures. The various parts of the yoke, 75 therefore, have been designated by the same reference characters as the yoke construc- 80 tion shown in Figs. 1 to 3 inclusive, and the parts of the key 11^a corresponding to like parts of the key construction of Figs. 1, 2 85 and 3 have been designated by the same numerals with the exponent letter "a."

While I have shown and described my im- 90 proved rail anchor in connection with two specific embodiments, it will be obvious 95 from the drawings and the foregoing de- scription that other modifications in struc- 100 ture might be made without departure from the spirit of my invention. I therefore wish it understood that my invention contem- 105 plates all rail anchoring devices coming within the scope of the appended claims.

I claim:

1. A rail anchor comprising two wedge members having an interlocking engage- 95 ment one within the other, one of said members being expanded when in its applied position to effect said interlocking engagement and to resist disengagement of the members. 100

2. A rail anchor comprising two members having an interlocking engagement one within the other, one of said members being expanded to provide a pocket for the reception of the other member, and adapted to 105 exert spring pressure against the other to resist the disengagement of the members.

3. A rail anchor comprising two wedge members having an interlocking engage- 110 ment one within the other, one of said mem- bers being resilient and adapted to exert spring pressure against the other to resist the disengagement of the members.

4. A rail anchor comprising two mem- 115 bers having an interlocking engagement one within the other, the inner member being expanded when in its operative position to effect said interlocking engagement and to resist the disengagement of the members.

5. A rail anchor comprising two members having an interlocking engagement one within the other, the outer member being formed to provide an enclosing pocket for the inner member, being expansible to permit the application of said inner member, 120 and being adapted to exert spring pressure against the other member to effect said interlocking engagement and to resist disengagement of the members. 125

6. A rail anchor comprising two members, 130

one being substantially enclosed by the other and having an interlocking engagement therewith, both of said members being expansible and adapted to exert pressure one 5 against the other to resist disengagement of the members.

7. A rail anchor comprising two channel-shaped members having an interlocking engagement one within the other, one of said 10 members being expanded when in its operative position to effect said interlocking engagement and to resist disengagement of the members.

8. A rail anchor comprising two channel-shaped members one being movable longitudinally within the other and having an interlocking engagement with the inner 15 walls thereof, one of said members being resilient and adapted to exert pressure against 20 the other to resist the disengagement of the members.

9. A rail anchor comprising a rail base embracing member formed with a channel having a normally restricted opening at one 25 end to provide a pocket and a key member having an interlocking engagement with the walls of said pocket, one of said members being resilient and adapted to exert spring 30 pressure against the other to maintain said interlocking engagement.

10. A rail anchor comprising a channel-shaped yoke for engaging opposite edges of a rail base, and a key member having an interlocking engagement within said yoke 35 member, one of said members being resilient and adapted to exert pressure against the other to maintain said interlocking engagement.

11. A rail anchor comprising a rail base embracing member channel-shaped in cross 40 section and a channel-shaped key having an interlocking engagement within said embracing member, the said key being expansible to resist the disengagement of the 45 members.

12. A rail anchor comprising a rail base embracing member channel-shaped in cross-section and a key channel-shaped in cross-section adapted to be driven between said 50 embracing member and the base of a rail, both of said members being expansible and adapted to exert pressure one against the other to resist the disengagement of the members.

55 13. A rail anchor comprising a rail base embracing member channel-shaped in cross-section and a channel-shaped key having an interlocking engagement with the inner walls of said member, one of said members 60 being resilient and adapted to exert pressure against the other to maintain said key in its interlocking position.

65 14. A rail anchor comprising a jaw member and a key member movable longitudinal- 70 ly of and having an interlocking engage- 75

ment with the other, said members having coengaging tapered surfaces whereby the key may be wedged between the jaw member and the rail to effect a gripping engagement of the jaw member on one of the base flanges 70 of the rail and provided with coengaging surfaces which taper in a direction to resist rearward movement of said casing; the jaw member being expansible and adapted to exert pressure against the other of the members, to resist disengagement of the members. 75

15. A rail anchor comprising a jaw member and a key member having coengaging tapered surfaces whereby relative movement of the members in one direction effects a 80 gripping engagement of the jaw member on one of the base flanges of the rail and effects an interlocking engagement of the members one within the other; one of said members being contractile to permit the entrance of 85 one of the members within the other and adapted to exert pressure against the other member to maintain said interlocking engagement.

16. A rail anchor comprising a jaw member and a key member having an interlocking engagement one within the other, and having coengaging tapered surfaces whereby relative movement of the members in one direction effects a gripping engagement of 90 the jaw member on one of the base flanges of the rail; the jaw member being expansible to permit entrance of the key member, and adapted to exert spring pressure against said key to maintain it in its operative position. 100

17. A rail anchor comprising a jaw member and a key member having an interlocking engagement one within the other, and having coengaging tapered surfaces whereby the key may be wedged between the jaw member and the rail to effect a gripping engagement of the jaw member on one of the base flanges of the rail; the key member being contractile to permit entrance of the 110 same within the jaw member and adapted to exert spring pressure against said jaw member to maintain the members in their interlocking position. 115

18. A rail anchor comprising a jaw member for engaging opposite edges of a rail base, and a key, both of said members having coengaging tapered surfaces whereby movement in one direction of one member with relation to the other effects a gripping engagement of the jaw member on the rail, said members being provided with coengaging tapered surfaces disposed in opposition to a rearward movement of the key member. 120

19. A rail anchor comprising a jaw member for engaging one edge of a rail base, and provided with tapered wedge surfaces which diminish in depth and increase in width toward one end thereof, and a key member having corresponding tapered surfaces and 130

adapted to be interposed between said jaw member and the rail; one of said members being resilient to permit engagement of one member within the other and adapted to exert spring pressure against the other to maintain a resilient interlocking engagement of the members.

20. A rail anchor comprising a jaw member for engaging an edge of a rail base and provided with tapered wedge surfaces which diminish in depth and increase in width toward one end thereof, and a key member having corresponding tapered surfaces and adapted to be interposed between said jaw member and the rail; the jaw member being expandible to receive the key and adapted to exert spring pressure against the key to maintain a resilient interlocking engagement of the members.

20. 21. A rail anchor comprising a jaw member for engaging one edge of a rail base and provided with tapered wedge surfaces which diminish the effective depth and increase the effective width of the member toward one end thereof, and a key member having corresponding tapered surfaces; the key member being contractile so as to be embraced by said jaw member and cooperate with said tapered wedge surface, and adapted to exert pressure against said jaw member to maintain its wedging engagement.

22. A rail anchor comprising a channel-shaped yoke adapted to engage opposite edges of a rail base and a key embraced by said yoke adapted to be forced into a wedging position between said yoke and the rail base, the key being of greater width at its entrance end than the receiving opening of said yoke, and the yoke being expandible to permit the entrance of said key.

23. A rail anchor comprising a channel-shaped yoke adapted to engage opposite edges of a rail base, and a key embraced by said yoke adapted to be forced into a wedging position between said yoke and said rail base, the key being of greater width at its entrance end than the receiving opening of said yoke, and the key being contractile to facilitate its entrance into said yoke.

20. 24. A rail anchor comprising a channel-shaped yoke adapted to engage opposite edges of a rail base, and a key embraced by said yoke adapted to be forced into a wedging position between said yoke and the rail base, the key being of greater width at its entrance end than the receiving opening of said yoke, and the key being U-shaped in cross-section so as to yield during its entrance into said yoke.

20. 25. A rail anchor comprising a channel-shaped yoke member provided at each end with spaced jaws for engaging the opposite edges of a rail base, and a key member adapted to be forced into a wedging position between said yoke and the rail; one of said

members being yieldable to permit the insertion of the key member into the channel portion of said yoke.

26. A rail anchor comprising a yoke member provided at each end with spaced jaws for engaging the opposite edges of the rail base, and with a channel-shaped body portion which decreases in depth toward one end and decreases in width toward the other end, and a key formed at one end of greater width and of less depth than the narrow end of the yoke and decreasing in width and increasing in depth toward the other end; one of said members being yieldable to permit the entrance of the wide end of the key into the narrow end of said yoke.

27. A rail anchor comprising a yoke member provided at each end with spaced jaws for engaging the opposite edges of a rail base, and with a channel-shaped body portion which decreases in depth toward one end and decreases in width toward the other end, and a key formed at one end of greater width and of less depth than the narrow end of said yoke and decreasing in width and increasing in depth toward the other end; the yoke being expandible to permit the entrance of the wide end of the key into the narrow end of the yoke, and adapted to contract to effect an interlocking engagement of said key and yoke as the key is moved towards the wide end of the yoke.

28. A rail anchor comprising a yoke member provided at each end with spaced jaws for engaging the opposite edges of a rail base, and with a channel-shaped body portion which decreases in depth toward one end and decreases in width toward the other end, and a key formed at one end of greater width and of less depth than the narrow end of said yoke and decreasing in width and increasing in depth toward the other end; the said key being contractile to permit the entrance of its wide end into the narrow end of the yoke and being adapted to expand to conform to the contour of the yoke when the key is moved toward the wide end of the yoke.

29. A rail anchor comprising a yoke member provided at each end with spaced jaws for engaging the opposite edges of a rail base, and with a channel-shaped body portion which decreases in depth toward one end and decreases in width towards the other end, and a key formed at one end of greater width and of less depth than the narrow end of said yoke and decreasing in width and increasing in depth toward the other end; both of said members being yieldable to permit the entrance of the wide end of said key into the narrow end of said yoke, and adapted to exert spring pressure one against the other to resist the disengagement of said members.

30. A rail anchor comprising a yoke mem-

ber provided at each end with spaced jaws for engaging the opposite edges of a rail base, and with a channel-shaped body portion which decreases in depth towards one end and decreases in width towards the other end, and a key of less length than the yoke and formed at one end of greater

width and of less depth than the narrow end of said yoke and decreasing in width and increasing in depth toward the other end; 10 one of said members being yieldable to permit the entrance of the wide end of the key into the narrow end of said yoke.

HAROLD G. WARR.
